UNITED STATES PATENT OFFICE

140,662

DESIGN FOR A VEHICLE-MOUNTED CRANE

George V. Johnson, Portland, Oreg., assignor to
Hyster Company, Portland, Oreg., a corporation
of Oregon

Application January 24, 1945, Serial No. 117,564

Term of patent 14 years

(Cl. D14—3)

To all whom it may concern:

Be it known that I, George V. Johnson, a citizen of the United States, residing at Portland, in the county of Multnomah and State of Oregon, have invented a new, original, and ornamental Design for a Vehicle-Mounted Crane, of which the following is a specification, reference being had to the accompanying drawings, forming part thereof.

Fig. 1 is a front perspective view of a vehicle-mounted crane showing my new design; and

Fig. 2 is a view in perspective, showing the rear, top, and right side of the design.

I claim:

The ornamental design for a vehicle-mounted crane, as shown.

GEORGE V. JOHNSON.
